(57) **CLAIM**

The ornamental design for a combined cup and lid as shown and described.

DESCRIPTION

FIG. 1 is a top perspective view of a combined cup and lid, showing my new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is a bottom perspective view thereof.

The broken lines shown in the drawings represent unclaimed portions of the combined cup and lid and form no part of the claimed design.
